[57] CLAIM

The ornamental design for a bay window, as shown and described.

DESCRIPTION

FIG. 1 is a front elevational view of a bay window showing our new design, the shutters being shown in retracted position;

FIG. 2 is a right side elevational view thereof, the left side elevational view being a mirror image thereof;

FIG. 3 is a rear elevational view thereof;

FIG. 4 is a top plan view thereof;

FIG. 5 is a bottom view thereof;

FIG. 6 is a front elevational view thereof, the shutters being shown in partially closed position;

FIG. 7 is a right side elevational view thereof, the left side elevational view being a mirror image thereof;

FIG. 8 is a rear elevational view thereof;

FIG. 9 is a front elevational view thereof, the shutters being shown in fully closed position;

FIG. 10 is a right side elevational view thereof, the left side elevational view being a mirror image thereof; and,

FIG. 11 is a rear elevational view thereof.
